United States Patent Office

Des. 192,230
Patented Feb. 13, 1962

192,230

SPOON HOLDER OR SIMILAR ARTICLE

Adeline R. Zucca, CMR-14, Allen Ave., P.O. Box 497, Vineland, N.J.

Filed Aug. 31, 1961, Ser. No. 66,579

Term of patent 14 years

(Cl. D44—29)

FIG. 1

A spoon is shown in broken lines in both figures for illustrative purposes.

I claim:

The ornamental design for a spoon holder or similar article, as shown and described.
